UNITED STATES PATENT OFFICE.

EUGENE PITOU, OF NEW YORK, N. Y.

WINDOW-WASHING APPARATUS.

Application filed April 26, 1922. Serial No. 556,727.

To all whom it may concern:

Be it known that I, EUGENE PITOU, a citizen of the United States, and a resident of the borough of Manhattan, county and 5 State of New York, have invented certain new and useful Improvements in Window-Washing Apparatus, of which the following is a specification.

This invention relates to an improved 10 window washing apparatus and in its broader aspects comprehends means whereby the washing of the windows of modern factories or industrial establishments, may be expedited. As is well known, in the modern 15 type of such buildings provision is made for obtaining a maximum of light and ventilation, and to this end the greater part of each wall of the building is composed of panes of glass. Unless the exterior surface 20 of these glass panes are cleaned at more or less frequent intervals, the collection of dust and dirt thereon will render the same semiopaque and impede or obstruct the penetration 25 of the sun's rays to such an extent that the advantageous results from the standpoint of sanitation and the health of the employees which it was aimed to secure in 30 the erection of the building, is, to a large extent, frustrated.

Owing to the fact that the cleaning of 35 such factory windows is a more or less difficult, laborious and time-consuming operation, the windows are washed or cleaned very infrequently and then, in a hurried and inadequate manner. By means of the present invention I aim to provide a simple and 40 comparatively inexpensive apparatus which will enable such extensive areas of glass windows to be expeditiously, as well as thoroughly cleaned whenever the necessity therefor arises with relatively little manual labor.

To this end, in one embodiment of my 45 proposed invention, a suitable scaffold is suspended from an inclined rail arranged beneath the roof cornice of the building, the suspending means including cables connected to suitable hoisting devices carried by the scaffold so that the latter can be readily 50 raised or lowered whenever necessary. Suitable means is also provided to be operated by the workmen on the scaffold which co-operates with a toothed portion of the rail to hold the suspended scaffolding against

gravity movement longitudinally of the inclined rail so that the scaffold may be retained at any desired position with respect to the building wall.

It is also one of the important objects of my invention to provide means whereby 60 the travelling carriage of the scaffold suspension means can be readily moved around the corner of the building without displacing said carriage from the continuously inclined rail.

With the above and other objects in view, the invention consists in the improved window washing apparatus and in the form, construction and relative arrangement of the several parts thereof as will be herein-after more fully described, illustrated in the accompanying drawings and subsequently incorporated in the subjoined claims.

In the drawings wherein I have disclosed one simple and practical form of the invention and in which similar reference characters designate corresponding parts throughout the several views:

Figure 1 is a perspective view showing a section of a factory or other building equipped with my improved window washing apparatus:

Fig. 2 is an enlarged transverse section illustrating the manner of mounting the scaffold suspending means upon the wall 85 of the building;

Fig. 3 is a diagrammatic view showing the arrangement of the continuous inclined rail;

Fig. 4 is a detail section showing the rack and pawl means for holding the scaffold against movement longitudinally of the rail;

Fig. 5 is a detail fragmentary perspective view of the supporting rail;

Fig. 6 is an enlarged detail elevation of a part of the scaffold suspension means; and

Fig. 6a is a similar view showing a slight modification;

Fig. 7 is a detail perspective view of one end of the scaffold and the suspension means therefor.

In the drawings I have illustrated a conventional and well known type of the modern factory building in which each of the four side walls of the building is largely made up of numerous relatively small glass panes 5. Beneath the cornice 6 of the build-

ing a substantially continuous rail is mounted. As herein shown, this rail consists of two angle bars 7, arranged in opposed relation and fixed at intervals to the wall brackets 8 with the adjacent edges of the horizontally disposed flanges spaced apart.

Upon referring to Figure 3 of the drawings it will be observed that in starting from one corner of the building, this supporting rail extends at a downward inclination around the four sides of the building.

Accordingly, it will be seen that the starting end of the rail is at a higher elevation than the opposite end thereof. A switching rail 8 connects this lowermost end of the rail 7 to said rail adjacent to the higher end thereof. It will be understood that the rail members 7 are slightly rounded at each corner of the building.

From the rail 7 the scaffold structure 9 is suspended. The suspension means for the scaffold includes a carriage consisting of two bars 10 hingedly connected to each other as at 11. At their other ends these carriage bars are also connected to the carriage trucks 12 by means of spring hinges 13, the frame of each truck being mounted between spaced pairs of wheels traveling on the horizontal flanges of the rail members 7 and depending between said flanges as clearly shown in Figs. 2 and 6 of the drawings.

Upon each end of the scaffold structure 9 which may be of any approved construction, a hoisting device 14 is mounted, said device including a take-up drum for the cable 15, said cables being respectively attached to the spaced wheel supported frames of the carriage.

In order to retain the scaffold structure in an adjusted position and prevent the gravitational movement thereof longitudinally along the inclined supporting rail, I provide the underside of the horizontal flange of one rail member 7 with the teeth 16 with which one end of a pivoted pawl or dog 17 is normally held in engagement by means of a spring 18. This dog is mounted upon one of the depending wheel supported frames of the carriage and to the end thereof, which is engaged with the teeth 16, the upper end of a wire or rope 19 is attached. This wire is automatically wound upon the slack take-up spool 20 which is suitably mounted in the supporting frame for one of the hoisting devices 14 so that as the scaffold structure is elevated by the operation of the hoisting devices, the slack in the wire 19 will be automatically taken up.

In Fig. 6^a of the drawings I have shown an alternative form of the braking means for the scaffold wherein the teeth 16 are eliminated and in lieu of the dog 17 a cam member 17' is provided. This cam member is pivotally mounted at one of its ends upon the carriage truck 12 and at its other end is

faced upon its upper edge with a suitable material of a frictional nature, said edge of the cam member being normally held in contact against the underside of the flange of the rail 7 by a suitable spring 18'. 70

In the operation of the improved window washing apparatus, starting from the higher end of the inclined rail 7 at one corner of the building with the scaffold at the lower end of the first vertical sub-division of the building wall, all of the windows in such sub-division are first washed, the scaffold structure being gradually elevated by the operation of the hoisting devices. The operator then pulls the wire 19 to release the holding dog 17 so that the carriage will gravitate longitudinally along the inclined supporting rail until the scaffold is positioned opposite the next vertical tier of windows. As the washing of this tier of windows progresses, the scaffold is gradually lowered. The holding dog 17 is then again released and the operations above described repeated until all of the windows along one side of the building have been washed. Upon arriving at the corner of the building with the scaffold structure adjacent to the ground, the workmen get off of the scaffold and move the same around the corner of the building, pulling upon the cables 15 so as to cause the carriage trucks 12 to move around the bended corners of the supporting rail. 90

Upon each end of the scaffold structure 9 which may be of any approved construction, a hoisting device 14 is mounted, said device including a take-up drum for the cable 15, said cables being respectively attached to the spaced wheel supported frames of the carriage. 100

In order to retain the scaffold structure in an adjusted position and prevent the gravitational movement thereof longitudinally along the inclined supporting rail, I provide the underside of the horizontal flange of one rail member 7 with the teeth 16 with which one end of a pivoted pawl or dog 17 is normally held in engagement by means of a spring 18. This dog is mounted upon one of the depending wheel supported frames of the carriage and to the end thereof, which is engaged with the teeth 16, the upper end of a wire or rope 19 is attached. This wire is automatically wound upon the slack take-up spool 20 which is suitably mounted in the supporting frame for one of the hoisting devices 14 so that as the scaffold structure is elevated by the operation of the hoisting devices, the slack in the wire 19 will be automatically taken up. 110

When the scaffold returns to the starting point at the lower end of the rail 7, by a sudden or quick pull upon the suspending cables 15, the traveling carriage is caused to move over the switch rail 8 so that it will again be positioned upon the uppermost end of the inclined rail 7. When the apparatus is not in use, the scaffold structure may be elevated to a position immediately beneath the uppermost windows where it will not obstruct the vision and in a position so that the workmen may readily have access thereto from the interior of the building when it 120

125

130

again becomes necessary to wash the windows.

From the foregoing description considered in connection with the accompanying drawings, the construction, manner of use and several advantages of the invention will be fully understood. It will be seen that I have provided a window washing apparatus which will be highly convenient and serviceable in use and particularly advantageous for the purpose of washing the extensive areas of glass window panes such as are provided in the erection of modern industrial buildings. The apparatus as herein disclosed is also relatively simple so that the application of the same for use upon existing building structures will not involve a considerable financial outlay.

In the foregoing description I have referred to a particular means for suspending the scaffold structure from the inclined supporting rail and for adjustably retaining the scaffold in various positions along the length of the rail. Such disclosure, however, is purely suggestive and in practice it may, in many cases, be found necessary or desirable to adopt other alternative means for affecting the movement and positioning of the scaffold structure as the window washing operation progresses. Therefore, it is to be understood that while I have herein described one simple and practical embodiment of the invention, the device is nevertheless susceptible of various modifications in the form, proportion and relative arrangement of the several parts. Accordingly, I reserve the privilege of resorting to all such legitimate changes as may be fairly embodied within the spirit and scope of the invention as claimed.

I claim:

1. In a window washing apparatus, wall brackets, a horizontally inclined rail mounted upon said brackets, carriage trucks mounted upon said rail, connecting bars hinged together and to said trucks, a scaffold secured to said trucks, hoisting devices carried by said scaffold and connected to said trucks, and means pivotally mounted upon said trucks engaging said rails for adjust-

ably holding the carriages against travelling movement upon said rail.

2. In a window washing machine, wall brackets, a rail mounted upon said brackets and consisting of angle bars arranged in opposite relation and fixed at intervals to the wall brackets with the adjacent edges of the horizontally disposed flanges spaced apart, carriage trucks mounted between the spaced flanges of said bars and having wheels, travelling on the horizontal flanges of said rail, said trucks depending between said flanges, hinged bars directly connecting said trucks, a scaffold secured to said depending trucks, hoisting devices carried by said scaffold and connected to said trucks, and means pivotally mounted upon said trucks engaging said rails for adjustably holding the carriage against travelling movement upon said rail.

3. In a window washing apparatus, wall brackets, a rail mounted upon said brackets and provided with a flange having teeth on its under surface, carriage trucks mounted upon the flange of said rail, bars flexibly connecting said trucks, a scaffold secured to said trucks, hoisting devices carried by said scaffold and connected to said trucks, and means pivotally mounted upon said trucks engaging the tooth surface of said rail for adjustably holding the carriage against travelling movement upon said rail.

4. In a window washing machine, wall brackets, a continuous supporting rail inclined horizontally along each side of a building, and consisting of angle bars arranged in opposite relation to each other with adjacent edges of their horizontally disposed flanges spaced apart, carriage trucks mounted upon said rail, means for flexibly connecting said trucks together, a scaffold secured to said trucks, hoisting devices carried by said scaffold and connected to said trucks, and means mounted upon said trucks engaging said rails for adjustably holding the carriages against travelling movement upon said rail.

In testimony that I claim the foregoing as my invention, I have signed my name hereunder.

EUGENE PITOU.
